UNITED STATES PATENT OFFICE.

CHARLES W. SWINGLEY AND HARRY MILLER, OF ST. LOUIS, MISSOURI.

DOWNDRAFT HOT-AIR FURNACE.

Application filed February 12, 1926. Serial No. 87,860.

This invention pertains to air heating furnaces, particularly those of the domestic type.

One of the objects of this invention is to provide an improved type of air heating furnace in which the down draft principle of combustion of the fuel may be employed.

Another object is to provide such a furnace having improved facilities for bringing the air to be heated in contact with the heating surfaces.

Further objects will appear from the following description taken in connection with the accompanying drawings in which:

15 Figure 1 is a front view of a furnace embodying this invention;

Figure 2 is a plan view partly in section of the same; and

20 Figure 3 is a side view of the same, showing parts in section.

In the accompanying drawings, 1 designates a fire box which may be constructed of cast iron or other suitable material and which has mounted therein an upper grate 2 and a lower grate 3. The lower grate may be of any suitable construction well known in the art. The upper grate 2 is constructed of a series of parallel tubes, running from front to rear of the fire box, and preferably inclined slightly upwardly toward the rear. The furnace may be provided with clean-out doors 4 and 5 providing access respectively to the space over the grate 3 and to the ash pit.

35 A firing door 6 is provided above the upper grate 2. The fuel is supplied through this door to the upper grate. After partial combustion upon the upper grate, during which the volatile ingredients of the fuel are usually given off, the coal, in the form of coke, drops through the upper grate to the lower grate. On the lower grate the coked fuel completes its combustion, after which the ashes fall through to the ash pit.

45 The firing door 6 is provided with an air inlet 7 having a damper of any suitable design and through which air for combustion of the fuel is admitted. This air passes over the upper grate 2 and downwardly therethrough. During this passage it supplies oxygen to the fire on the upper grate and also carries the unburned gases produced thereby downwardly to the lower fire. During the progress of the air over the lower grate 3, it supplies oxygen for the combustion of the coke on that grate

and also carries the unburned gases into contact with the lower fire by which they are completely consumed, so that the furnace operates practically without smoke. After 60 passing over the lower fire-bed, the gases pass out through a flue opening 8 to the smokestack 9. A clean-out 10 connects with a clean-out door 11 for the removal of the soot deposits.

65 Surrounding the fire box 1 is a jacket 12. This may be constructed of cast iron, fire brick or any other suitable material. A space 13 is left between the fire box 1 and the jacket 12 for the circulation of the air to be heated. The front of the furnace is provided with openings 14, having dampers 18, for the admission of the air to be heated, which circulates through the space between the fire box and the jacket so as to come 70 in contact with the heated surfaces of the fire box and then passes to the rear of the jacket and out to the air distributing system by means of the hot air pipes 15. The front of the furnace may also be provided at its upper portion with one or more inlet openings 16 provided with suitable dampers 17 through which air may be admitted at the top when desired.

75 The hollow grate bars of the upper grate 2 extend through the front and rear of the fire box and are open at both ends. They are therefore adapted to receive air from the front of the furnace carrying the same 80 through the heated tubes and delivering it to the rear portion of the jacket and eventually to the pipes 15. The rearward and upward incline given to these pipes causes the heated air to flow upwardly therealong so that a continuous draft of air is passing through 85 said pipes. This draft serves not only to heat the passing air, but also to cool the grate bars so as to prevent overheating of 90 the same.

95 It will be seen, therefore, that this invention provides a simple and effective air heating furnace for domestic use. The down draft arrangement of the two grates provides for a complete combustion of the fuel so that the operation is practically smokeless. Provision is made for passing the air to be heated not only around the fire box but also through the hollow grate bars so that a great quantity of air at a high temperature is delivered to the distributing system.

100 105 110 It is obvious that various changes may be made in the details of construction with-

out departing from the spirit of this invention; it is to be understood, therefore, that this invention is not limited to the specific details shown and described.

5 Having thus described the invention, what is claimed is:

1. A down draft furnace comprising a fire box, an upper grate, a lower grate, a draft inlet to said fire box above said upper grate, an outlet from said fire box below said upper grate, an air jacket surrounding said fire box and a smoke flue within said jacket and connecting with said outlet.
- 15 2. An air heating furnace comprising a fire box having its outlet at the lower part thereof, and a flue leading therefrom, an upper grate above said outlet, a lower grate below said outlet adapted to receive fuel from said upper grate, a draft inlet to said fire box above said upper grate, an air jacket surrounding said fire box and flue and provided with an air inlet, and air distributing means connected with said jacket and receiving the hot air therefrom.
- 25 3. An air heating furnace comprising a fire box having its outlet at the lower part thereof and a flue leading therefrom, an upper grate above said outlet, a lower grate below said outlet adapted to receive fuel from said upper grate, a draft inlet to said fire box above said upper grate, an air jacket coextensive with said fire box adjacent said grates and enclosing said flue and provided with an air inlet, and air dis-

tributing means connected with said jacket and receiving the hot air therefrom.

4. An air heating furnace comprising a fire box, an upper hollow grate, a lower grate, a draft inlet to said fire box above said upper grate, an outlet from said fire box below said upper grate and a flue leading therefrom, air distributing means around said flue receiving air from said hollow grate adjacent the flue.

45 5. An air heating furnace comprising a fire box, an upper grate, a lower grate, a draft inlet to said fire box above said upper grate, an outlet from said fire box below said upper grate, an air jacket surrounding said fire box, an air inlet for said jacket at the front of the furnace above said fire box, and air distributing means connected with said jacket and receiving the hot air therefrom.

55 6. An air heating furnace comprising a fire box, an upper grate, a lower grate, a draft inlet to said fire box above said upper grate, an outlet from said fire box above said upper grate, an air jacket surrounding said fire box, an air inlet for said jacket at the front of the furnace above said fire box, means for controlling the flow of air through said jacket, and an air distributing means connected with said jacket and receiving the hot air therefrom.

60 In testimony whereof we affix our signatures.

CHARLES W. SWINGLEY.
HARRY MILLER.
